UNITED STATES PATENT OFFICE.

JOHN ALOYSIUS MATHERS, OF GRENFELL, SASKATCHEWAN, CANADA, ASSIGNOR OF ONE-THIRD TO MARCUS HIBBITS NEILL AND GARNET CEDRIC NEFF.

ENVELOP MOISTENER AND SEALER.

1,241,645.

Specification of Letters Patent.

Patented Oct. 2, 1917.

Application filed March 9, 1917. Serial No. 153,556.

To all whom it may concern:

Be it known that I, JOHN A. MATHERS, a subject of the King of Great Britain, residing at Grenfell, Province of Saskatchewan, Canada, have invented certain new and useful Improvements in Envelop Moisteners and Sealers; and I do hereby declare that the following is a full, clear, and exact description of the invention, such as will enable others skilled in the art to which it appertains to make and use the same.

The present invention relates to an envelop moistener and sealer and has for its object to provide a simple article of this character which will readily moisten the gummed flaps of envelopes and seal the envelopes within a single operation, thereby permitting a larger number of envelopes to be sealed in a short space of time.

20 A further object of the present invention is to provide a strong, durable and efficient device of this character which will be inexpensive in the cost of manufacture, thereby rendering the same commercially desirable.

25 With the above and other objects in view which will hereinafter appear as the description continues, the invention consists of the novel features of construction, combination and formation of parts as will be hereinafter more fully described and particularly pointed out in the appended claims.

In the accompanying drawings has been shown the simple and preferred form of the invention, it being, however, understood that 35 no limitation is necessarily made to the precise structural details herein exhibited, but the right is hereby reserved to any changes, alterations or modifications to which recourse may be had that come within the 40 scope of the claims without departing from the spirit of the invention or sacrificing the efficiency of the same.

In the accompanying drawings:

Figure 1 is a perspective view of the device embodying the present invention as applied to use;

Fig. 2 is a side elevation of the same; and, Fig. 3 is a vertical cross section.

Referring now more particularly to the 50 accompanying drawings wherein like and corresponding parts are designated by similar reference characters throughout the several views.

The device forming the subject matter of 55 the present invention comprises a U-shaped

frame 1 having journaled within its opposite ends a roller 2 and the transverse bar of this frame has connected thereto a handle 3.

An elongated tank or reservoir 4 is provided, which is detachably connected to the frame 1 having mounted at its lower end a moistener which is adapted to rub over the gummed flaps of envelopes for moistening the same. Secured to the forward upper end of the tank 4 by means of the brackets 5 is a bar 6. One end of this bar 6 is adapted to project through an opening formed within the side bar 7 of the frame 1, whereas the opposite side bar 8 of the frame is provided with a slot 9 in which the opposite end of the rod 6 rests and a pivoted latch member 10 is carried by the bar 8 for retaining the rod 6 within the slot 9. Pivottally connected to the bar 7 is an L-shaped bracket 11 having a recess in its shorter arm in which is adapted to rest a lug 12 carried by the side wall of the tank 4. Also carried by the bar 7 is a leaf spring 13 normally resting upon the bracket 11, thereby providing a cushional support for the pivotally mounted tank 4.

Arranged within the tank 4 is a partition 14 dividing the same into two compartments, one of which indicated by the numeral 15 is for holding the water and the opposite compartment has a pair of rollers 16 journaled therein. Adapted to be wound upon the rollers 16 is a wick 17 or other suitable moistener which extends over the rounded lower portion 18 of the tank. These rollers 16 are provided with the handles 19 whereby the rollers may be turned in either direction. The partition 14 is provided with openings which are adapted to be closed by the slide valve 20 and this valve 20 has connected thereto a valve stem 21 which may be 95 manually opened or closed. The tank 4 is also provided with an opening which is shown closed by means of the cap 22. By removing the cap 22 a suitable supply of water may be placed within the compartment 15 and by opening the valve 21 this water may be supplied to the wick 17 as better shown in Fig. 3.

In the operation of the device the operator 105 grips the handle 3 and by forcing the device forward the roller 2 will open the gummed flap A of the envelop B and when the moistener comes in contact with the gummed portion of the flap A the gum thereon will be properly moistened. By reversing the 110

operation of the device and slightly raising the frame 1 the moistener will be raised out of contact with the flap of the envelop and the roller 2 will pull the flap A back over 5 upon the body portion of the envelop B where the flap will adhere to the envelop.

It is obvious from the foregoing that the envelopes may be moistened and sealed with this device without touching the envelopes 10 with the hands and that a larger number of envelopes may be sealed in a short period of time.

Having thus fully described my invention, what I claim as new and desire to secure by 15 Letters Patent is:

1. In a device of the character described the combination of a supporting frame, of a tank pivotally and detachably connected to said supporting frame, a partition formed 20 within said tank for dividing the same into two compartments, a valve controlled open-

ing being arranged within said partition, a pair of rollers journaled within one of said compartments, a moistener carried by said rollers and extending over the lower end of 25 said tank substantially as and for the purpose specified.

2. An envelop moistener of the character set forth comprising in combination a U-shaped frame, a tank, means for pivotally 30 connecting said tank within said U-shaped frame, a spring actuated bracket carried by said U-shaped frame and adapted to rest upon said tank, a moistener carried by the lower end of said tank and a 35 handle carried by the medial portion of said U-shaped frame.

In witness whereof I have hereunto set my hand at Grenfell aforesaid this 19th day of February, A. D. 1917.

JOHN ALOYSIUS MATHERS.
